(57) CLAIM

The ornamental design for a handbag, as shown and described.

DESCRIPTION

FIG. 1 is a front perspective view of a handbag showing my new design;

FIG. 2 is a front elevational view thereof;

FIG. 3 is a rear elevational view thereof;

FIG. 4 is a right side perspective view thereof;

FIG. 5 is left side perspective view thereof;

FIG. 6 is a top plan view thereof;

FIG. 7 is a bottom plan view thereof;

FIG. 8 is a front perspective view of a second embodiment thereof;

FIG. 9 is an enlarged perspective view of the lock portion thereof;

FIG. 10 is alternate enlarged perspective view of the lock portion thereof;

FIG. 11 is an enlarged perspective view of the key and key strap portion thereof;

FIG. 12 is an enlarged elevational view of the strap fastener portion thereof; and,

FIG. 13 is an enlarged elevational view of the buckle attachment portion thereof.

The broken lines showing a handbag are for the illustrative purposes only and form no part of the claimed design. The broken lines shown within the full line disclosure portions of the claimed design are understood to represent stitching and form no part of the claimed design.
